(57) **CLAIM**

The ornamental design for a computer screen display or portion thereof with graphical user interface, as shown and described.

DESCRIPTION

The FIGURE is a front view of a computer screen display or portion thereof with graphical user interface showing the new design.

The outermost broken line illustrates the computer screen display, and the broken line showing of alpha-numeric text within the outermost broken line illustrate portions of the graphical user interface. None of the broken lines form part of the claimed design.
